UNITED STATES PATENT OFFICE.

CYRIL A. BRIGHAM, OF EAST ORANGE, NEW JERSEY, ASSIGNOR TO BRANDES LABORATORIES, INC., OF NEWARK, NEW JERSEY, A CORPORATION OF NEW JERSEY.

SOUND-REPRODUCING APPARATUS.

Application filed November 2, 1926. Serial No. 145,809.

My invention relates broadly to electromagnetic sound reproducers and more particularly to an electromagnetic sound reproducer having a flat driving coil element arranged to deliver vibrations directly to a sound reproducing diaphragm.

One of the objects of my invention is to provide a sound reproducer in which an electromagnetic driving mechanism is provided with a flat driving element which substantially floats between the pole pieces of the electromagnetic driving mechanism for imparting vibrations to a sound reproducing diaphragm which directly connects to a flat driving element.

Another object of my invention is to provide an electromagnetic sound reproducer having a flat driving element therein for imparting vibrations to a diaphragm which is substantially free floating at the edge thereof.

Another object of my invention is to provide a sound reproducer wherein a sound reproducing diaphragm extends angularly in all directions from a flat vibratory element which is suspended within a variable magnetic field whereby mechanical vibrations initiated in the said flat vibratory element may be directly transferred to said sound reproducing diaphragm.

My invention will be more clearly understood by reference to the following specification and the accompanying drawings in which:

Figure 1 is an elevational view of the electromagnetic driving element and sound reproducing diaphragm of my invention; Fig. 2 is a plan view partially broken away and illustrated in cross-section showing the parts of the sound reproducing system of my invention; Fig. 3 is a cross-sectional view taken through the reproducer of my invention and showing the arrangement of the driving element with respect to the sound reproducing diaphragm; Fig. 4 is a cross-sectional view with the sound reproducing element shown partially in elevation and in cross-section on line 4-4 of Fig. 3; and Fig. 5 is a perspective view of the parts of the connecting means which are interposed between the sound reproducing diaphragm and the electromagnetic driving element.

Referring to the drawings in detail reference character 1 designates a panel mem-

ber which is apertured to permit a sound reproducing diaphragm to float therein with a rubber membrane 2 in the form of an annular ring disposed between the peripheral edge 5 on sound reproducing diaphragm 3 and apertured panel 1. The sound reproducing diaphragm is formed of relatively stiff material which is dished or gathered at its center into a flattened portion at 4 with a pair of parallel extending lip portions 5 and 6 projecting in a plane parallel to the axis of said sound reproducing diaphragm. The lip members 5 and 6 grip opposite faces of a flat coil support 7 which carries windings 8 and 9 on opposite sides thereof. The flat coil support 7 is extremely light in weight by reason of apertures 10 and 11 and the small mass of the material. Projections 11 and 12 are formed on the coil support 7 and these are secured in the buttons 14 and 15 which are carried by the spider member 16 which is suspended from the panel member 17. The electromagnetic sound reproducer includes a frame structure 25 which supports the panel members 17 and 18 on opposite sides thereof with the electromagnetic system 21 and 22 disposed therebetween. Conductive plate members 23 and 24 are secured over the pole pieces forming a gap within which the windings 8 and 9 are arranged to be laterally vibrated. Vibrations imparted to the windings 8 and 9 impart vibratory motion to the coil support 7, which in turn transfers the mechanical vibrations to the sound reproducing diaphragm 3. The entire vibratory system comprising the coil support 7, windings 8 and 9 and sound reproducing diaphragm 3 substantially floats in such position that the windings are subjected to an intense magnetic field within a narrow gap between the faces of plate members 23 and 24. The coil support 7 is suspended by means of laterally projecting flexible strip members 19 and 20 which are secured in slots 7^a and 7^b in the coil support 7 and attached at opposite ends to the sides of the apertured panel 18. The strip members 19 and 21 are constructed of such material as to be substantially rigid against movement in a direction parallel to the axis of pole pieces 21 and 22 while being extremely flexible for movement of coils 8 and 9 in a path normal to the axes of the pole pieces. I may employ strips of celluloid for

the members 19 and 20 and for the spider 16 which material possesses the property of rigidity in the direction of its length while being extremely flexible in a direction normal to its surface.

The vibratory system is substantially suspended between spider 16 at one end and by the strip members 19 and 20 at the opposite end, the sound reproducing diaphragm 3 being supported from the coil support 7 substantially in the form of a cantilever, the peripheral edge 5 of the sound reproducing diaphragm 3 being substantially free and unconfined inasmuch as the material 2 is extremely light and flexible and may itself possess the property of stretching by reason of its resilient characteristics. In many cases I leave a substantial amount of slack in the annular ring member 2 preventing injury to the peripheral edge of the sound reproducing diaphragm 5.

While I have described my invention in one of its preferred embodiments, I desire that it be understood that modifications may be made and that no limitations upon my invention are intended other than are imposed by the scope of the appended claims.

What I claim as new and desire to secure by Letters Patent of the United States is as follows:

1. An electromagnetic sound reproducer comprising an electromagnetic driving mechanism, a vibratory member actuated by said mechanism, a sound reproducing diaphragm, said diaphragm being substantially dished at the center thereof and having a pair of co-extensive parallel lip portions secured to said vibratory member whereby vibrations initiated in said vibratory member are transferred through said lips to said sound reproducing diaphragm.

2. An electromagnetic sound reproducer comprising an electromagnetic driving mechanism including a set of pole pieces, an element capable of vibration suspended between said pole pieces, a sound reproducing diaphragm which is substantially dished at its center, said diaphragm terminating in a pair of flat parallel tapered lip members, said lip members being attached to opposite sides of said vibratory element whereby vibrations initiated in said element are transferred to said sound reproducing diaphragm.

3. An electromagnetic sound reproducer comprising an electromagnetic system, a vibratory element arranged to be actuated by said electromagnetic system, a flat supporting member arranged to carry said vibratory element, a sound reproducing diaphragm, said sound reproducing diaphragm diverging from said supporting member, the material of said sound reproducing diaphragm overlapping on opposite sides of said supporting member and connected to

said member in such manner that mechanical vibrations initiated in said vibratory element may be transferred to said sound reproducing diaphragm.

4. In an electromagnetic sound reproducer, an electromagnetic driving mechanism including sets of pole pieces directed toward each other, a vibratory element disposed between said pole pieces and extending in the form of a flattened projection beyond said pole pieces, a sound reproducing diaphragm having a substantially circular periphery and being dished at the center thereof and terminating in a pair of flat parallel lip members, said lip members being spaced one from the other and secured to opposite sides of said flattened projection whereby vibrations initiated in said vibratory member may be transferred to said sound reproducing diaphragm.

5. In an electromagnetic sound reproducer, an electromagnetic driving mechanism including sets of pole pieces directed toward each other, a vibratory element suspended between said pole pieces in a plane normal to the axis thereof and free to vibrate between said pole pieces with substantially no inertia, said vibratory element terminating in a flattened extension projecting beyond the limits of said pole pieces, a sound reproducing diaphragm having a substantially circular outer periphery and converging toward said flattened extension, said diaphragm terminating in a pair of flat parallel extending lip portions secured to opposite sides of said flattened extension whereby vibrations initiated in said vibratory element may be transferred to said sound reproducing diaphragm.

6. An electromagnetic sound reproducer comprising a driving mechanism including sets of pole pieces directed toward each other, a vibratory element mounted between said pole pieces said vibratory element comprising a flat coil support and a pair of windings carried on said support, a sound reproducing diaphragm having a substantially rounded periphery, said diaphragm converging toward said coil support and enveloping opposite sides thereof, and means for suspending said coil support at opposite ends in a position in which said windings are free to vibrate in a plane normal to the axes of said pole pieces for transferring vibrations to said sound reproducing diaphragm.

7. An electromagnetic sound reproducer comprising an electromagnetic driving mechanism including a plurality of sets of pole pieces directed toward each other, a flat coil support, a pair of windings carried by said coil support, flexible strip members secured to opposite ends of said coil support in planes normal to the axis of said coil support whereby said coil support is free to vibrate

in a plane normal to the axis of said pole pieces, a sound reproducing diaphragm substantially rounded at its periphery and converging toward said coil support, said sound reproducing diaphragm terminating in a pair of flat parallel extending lip members on opposite sides of said coil support whereby vibrations initiated in said windings may be imparted to said sound reproducing diaphragm. In testimony whereof I affix my signature.

CYRIL A. BRIGHAM.
